CHILD'S VEHICLE

Clyde A. Scheppelle, Las Vegas, Nev.

Application February 3, 1953, Serial No. 23,407

Term of patent 7 years

(Cl. D34—15)

To all whom it may concern:

Be it known, that I, Clyde A. Scheppelle, a citizen of the United States, residing at Las Vegas, in the county of Clark and State of Nevada, have invented a new, original, and ornamental Design for a Child's Vehicle, of which the following is a specification, reference being had to the accompanying drawing, forming part thereof, wherein:

Fig. 1 is a side elevational view of a child's vehicle showing my new design, the left front wheel and the left rear wheel thereof being omitted for convenience of illustration only;

Fig. 2 is an elevational view of the child's vehicle taken from the side opposite that shown in Fig. 1, the right front wheel thereof being omitted for convenience of illustration only;

Fig. 3 is a bottom plan view thereof;

Fig. 4 is a top plan view thereof;

Fig. 5 is a rear elevational view thereof; and
Fig. 6 is a front elevational view thereof.

I claim:

The ornamental design for a child's vehicle, as shown and described.

CLYDE A. SCHEPPELE.
